UNITED STATES PATENT OFFICE

HARRY SWINGLEHURST, OF ORANGE, NEW JERSEY, ASSIGNOR TO SCOTT AND WILLIAMS INC., OF NEW YORK, N. Y., A CORPORATION OF MASSACHUSETTS

CIRCULAR-KNITTING MACHINE

Application filed March 16, 1922. Serial No. 544,179.

The object of my invention is to provide a circular knitting machine with means whereby splicing of varying width may be obtained automatically. My invention is especially applicable to the knitting of seamless hosiery, and by my improvements I can produce seamless hosiery with high splicing varying in width as for example, tapering, that is, gradually widening from a point or 10 a narrow width at the top to the ordinary width (about half the circle of needles) at the heel.

The foregoing object I attain in the manner which I will describe. My improvements 15 may take the form of an attachment to almost any form of circular knitting machine. In the accompanying drawings I have shown my improvements as applied to a Scott and Williams circular hosiery machine, in which 20 the needle cylinder revolves while the needle cams are stationary, but it will be understood that the invention may be applied to other types and constructions of circular knitting machines.

25 The general construction of the Scott and Williams hosiery machine is such as illustrated, for example, in the Scott Patents 1,148,055, July 27, 1915, and 1,152,850, Sept. 7, 1915.

30 In the accompanying drawings

Fig. 1 is a side elevation of sufficient of the knitting machine to show my attachment applied thereto;

Fig. 2 is a vertical section on the line 7—7, 35 Fig. 3;

Fig. 3 is a sectional plan on the line 3—3, Fig. 2;

Fig. 4 is a section through the variable cam on the line 4—4, Fig. 1;

40 Figs. 5, 6 and 7 are views of the disks composing the variable cam controlling the splicing;

Figs. 8 and 9 are views drawn to a larger scale to illustrate the cam-adjusting pawl feed;

Fig. 10 is a back view of part of a stocking, illustrating a tapering splicing.

In Fig. 1, H represents the bed plate of the machine, within which rotates on a vertical 50 axis, the needle cylinder 260 and surround-

ing the upper part of this is the sinker cam ring 300. To a post 400 on this bed plate is pivoted in the usual manner the latch ring 556, and to a suitable part of this latch ring are pivoted yarn-guiding fingers such as F. 55 These yarn fingers are severally lifted out of action or allowed by gravity to drop into action (that is, to positions to feed yarn to the needles) by thrust bars 460, which are guided in suitable parts of the frame and 60 are acted on at their lower ends by cam surfaces on a rotating pattern drum 120. These cam surfaces raise the thrust bars or allow them to drop and cause corresponding operation of the respective yarn guides as the cam 65 drum 120 is intermittently turned in the usual manner.

One of these yarn-guiding fingers F is a splicing yarn feed, which in the normal operation of the Scott and Williams hosiery 70 machine is dropped into action to feed yarn to the needles when the high splicing point is reached in knitting the stocking from the top to the toe. During the knitting of this high splice, according to the ordinary practice, suitable means provided for the purpose lift this splicing yarn guide out of feeding position during about half of each revolution of the knitting head and drop the yarn guide back into feeding position during the other 75 so half of the revolution. By this means the stocking is knitted with a spliced portion of uniform width throughout, that is, having parallel edges.

As already stated, it is the object of my 85 present invention to provide means whereby I can produce on a circular knitting machine a stocking or the like with a spliced section of varying width, such as a tapering high splice portion, as indicated, for example, at X in 90 the back view of part of a stocking indicated in Fig. 10.

In carrying out my present invention in connection with the Scott and Williams machine, I provide an automatically variable 95 cam which controls the time of throwing of the splicing yarn guide F into and out of operation at each revolution of the knitting head, and this is done preferably through its thrust bar 460. This variable cam is so con- 100

structed and operated that the portion of the cam, which controls the period of time during which the splicing yarn is being fed to the needles during each revolution, may be lengthened or shortened automatically between courses (every other course for example) in order that the desired varying width of splicing may be produced.

I fixedly attach to the main frame of the machine, at the rear thereof, a bracket B (Figs. 1 and 3) with bearings $b b'$ (Fig. 3) for a horizontal shaft A which is driven through suitable gearing (as a, a', a'' Fig. 3) from a moving part of the machine in such a way that this shaft A rotates in unison with the knitting head, that is, one revolution of this shaft A for each revolution of the knitting head—in this instance, the needle cylinder.

To the outer end of this shaft A (right hand end in Fig. 3) is secured the variable cam C. It is this rotary cam which controls the period of feed of the splicing thread at each revolution during the courses the splicing thread is fed in. Between the periphery of this cam C and the thrust bar 460, which raises the splicing yarn guide F, is interposed a bell-crank lever D, (Fig. 2) which is pivoted on a horizontal rod d carried by the bracket B. The lower arm of this pivoted lever D has a wide nose d' (Fig. 3) adapted during splicing to bear against the periphery of the cam C, while the other arm of this lever has a nose d'' adapted to act in a notch n in the splicing thrust bar 460 (Fig. 2). A spiral pull spring d^3 tends to keep this end of the lever D in this notch n at all times, holding the other arm d' of the lever D clear of the periphery of the cam C, so long as the thrust bar 460 is held in its elevated position by the cam 501 on the drum 120, that is, while the portions of the stocking not to be spliced are being knitted.

In Fig. 2, I have shown the lower end of the splicing thrust bar 460 as having dropped off the end of the cam surface 501 of the drum 120, as the latter is rotated intermittently in the direction of its arrow in that figure. In this same figure, the cam C is shown in that part of its revolution in which a depression c is opposite the end d' of the lever D; and this end of the lever has dropped into the depression under the weight of the thrust bar 460. So long therefore as this end d' of the lever D is in the depression c as the cam C revolves, the splicing yarn guide F will be in its lowered active position supplying the splicing yarn to the needles. The shorter the length of this depression the fewer needles will get the splicing thread at each revolution of the cam and knitting head.

I provide means for automatically adjusting the cam C so as to change the length of this depression c as the splicing progresses.

For this purpose, the cam C is built up of several parts or is in other words a compound cam, as shown more in detail in Fig. 4. It comprises three principal parts, a central disk 50 keyed to the shaft A (Fig. 3) and having on opposite sides cylindrical hubs 51, 52 on which are mounted disks 53 and 54 respectively, so that they can be caused to turn on these hubs 51, 52. The central disk 50 carries a radial pin 55 on which can turn a pinion 56. This pinion meshes into gears 57 on the inner faces of the two outer disks 53 and 54, so that when one of these two disks 53 is caused to turn in one direction the other disk 54 is, through the pinion 56, caused to turn in the opposite direction. I find it desirable to employ an expansion spring 80, Fig. 4, between the disks 53 and 54, at a point diametrically opposite the pinion 56. The peripheries of the three disks 50, 53 and 54 severally have the outlines shown in Figs. 5, 6 and 7, respectively, that is, each with a sunken part c . These three views Figs. 5, 6 and 7 are views of the three parts separated and looked at in the directions of the arrows at the planes 5, 5 and 6, 6 and 7, 7 respectively, Fig. 3.

As seen in Fig. 3, the end d' of the lever D is wide enough to extend across the three disks 50, 53 and 54, so that by suitably turning the outer disks 53 and 54 in opposite directions, the total length of the depressed portion c of these cam parts offered to the end of the lever D as seen in Fig. 2, may be varied from nothing up to the full length of the depression c in each of the disks.

In order to adjust the disks for this purpose, I provide a suitable pawl and ratchet movement. A ratchet R is secured to the side of the disk 54, and a pawl 58 is carried by a lever 59 pivoted at 60 to an arm 61 which is secured to the hub 52 of the central disk 50 fixed to the shaft A. The free end of this pawl lever 59 is caused by a spring 62 to bear against a cam or eccentric 63 which is carried on the outer end of a lever 64. This lever 64 is pivoted at 65 to an extension of the bracket B, and has its other end lying in the path of cams 66, 67 on the pattern drum 120. A spring 72, Fig. 1 tends to keep this lever 64 and cam 63 in the position shown in Fig. 1. When this lever is not being acted on by these cams 66, 67, the cam 63, which actuates the pawl lever 59, only imparts a short movement to the lever 59, as the latter is carried around by the shaft A and thereby a short feed movement is imparted to the pawl 58, but when one of the cams 66, 67 on the drum 120 raises the right hand end of the lever 64 and moves the cam 63 downwardly so as to carry its active lower side further away from the center of the shaft A, a greater movement will be given to the pawl lever 59, and a longer stroke will be given to the pawl 58 at that revolution.

At two points on the edge of the disk 54 and within the path of the pawl 58 (Fig. 1) are adjustably secured two idling points 68 and 69 in the form of high teeth, such that when the pawl 58 rides up on either of these teeth, the ordinary short feed movements will not move the pawl far enough to go off the point 68 (69), and consequently at every revolution of the shaft A, the pawl will simply idle on the point until the pattern drum 120 in the course of its intermittent feed movements brings one of the cams 66, 67 under the free end of the lever 64, and thereupon causes the active side of the cam or eccentric 63 to be moved outwardly radially from the axis of the shaft A, and so give a long movement to the feed pawl 58; then on the return of the pawl lever the pawl 58 will pass over the idling point 68 (69) so that the pawl can then resume its feed movements of the disks 54, 53.

From the foregoing description, it will be understood that in the case of the knitting of a stocking, for example, the cams on the pattern drum 120 will be so arranged that during the knitting of the main part of the leg, the thrust bar 460 which acts upon the splicing yarn guide F will be held in its elevated position by the cam 501 (Fig. 2) acting on the lower end of the thrust bar, but when the point is reached where the splicing is to begin, the rotation of the drum 120 will carry the end of the cam 501 from under the thrust bar 460, and consequently the splicing yarn guide F will drop to operative position, unless prevented by the action of the cam c' on the lever D, Fig. 2. The feed pawl for the disks of the cam C has meanwhile been idling on the point 68, but at the time the thrust bar 460 drops off the end of cam 501, the cam 66 on the pattern drum will come under the free end of lever 64, with the result of causing a long feed movement of the pawl 58, as already described, carrying it off the idling point 68. Then at each revolution this pawl will have feed movements imparted to it to turn the two disks 53, 54 gradually in opposite directions and so step by step to lengthen the depression c in the periphery of the compound cam C', and correspondingly increase step by step the number of needles which will take the splicing yarn. The effect will be to produce a spliced section in the back of the stocking of the tapering shape indicated in Fig. 10. I have found in practice that it is not desirable to change at every successive course the number of needles which take the splicing thread. It is preferable to make this change at recurrent courses, as at every other course. In practice, I provide means whereby during splicing the disks 53, 54 are adjusted, that is, have feed movements imparted to them by the pawl 58 only at every other revolution of the knitting head and shaft A.

To accomplish this, I provide in addition to the ratchet R, which is secured to the disk 54, a ring 70 (Fig. 4) which is mounted frictionally on this disk and has coarse ratchet teeth, each tooth just twice the length of each of the teeth of ratchet wheel R (Figs. 3, 8 and 9). The pawl 58 has a nose wide enough to extend over both the ratchet wheel R and the adjacent ratchet ring 70. A secondary pawl 71, which is mounted on the same pivot as the pawl 58 on lever 59, is adapted to engage the teeth of ratchet ring 70. This pawl is of a different length from the pawl 58, but is so arranged that when the nose of pawl 58 is at the forward end of one of its regular feed strokes, the pawl 71 will be on the top of one of the teeth of ratchet 70, as shown in Fig. 8. Then on the return movement of the pawl lever, under the action of its spring 59' (Fig. 1), both pawls will move back over the ratchet teeth, but while pawl 71 will drop back of the tooth on which it was riding, the pawl 58 will ride up onto the top of a tooth of the coarse ratchet 70, as seen in Fig. 9. Then at the next revolution of the cam shaft A, when a forward movement is imparted to the pawl lever 59, the pawl 58 (Fig. 9) can not engage the teeth of ratchet disk R, being held up by the coarse tooth of ring 71, and at this movement there will be no feed movement imparted to the disks 53, 54. But since the pawl 71 is in engagement with a tooth of ratchet ring 70 (Fig. 8), the effect will be to move the latter rotarily on the disk 54 to an extent equal to the stroke of the pawl lever 59 and consequently on the return stroke of this pawl lever 59, the pawl 58 can drop back of the tooth of ring 70, on which it had been riding and into engagement also with a ratchet tooth of the disk R (Fig. 9) and therefore at the next revolution a feed movement will be imparted to the disks 53, 54 to increase the length of the depression c at the periphery of cam wheel C.

These feed movements with consequent lengthening of the depression c in the variable cam C' will thus continue at every other revolution until the desired full width of splicing is obtained, namely that about equal to half the circle of needles. The idling point 69 will then have reached the pawl 58, and the latter, under the ordinary movements of its pawl lever 59, will ride idly back and forth on the point 69, until the cam 67 on the pattern drum comes under the free end of the lever 64 and raising that free end, causes the active side of the cam or eccentric 63 at the other end to be moved radially outward from the axis of the shaft A and thus to give to the pawl lever 59 an extra long feed movement, with the result that on the return the pawl 58 will pass off the idling point 69 and engage the ratchet teeth of the disk 53.

and resume intermittent feeding of the disks 53, 54.

This, however, will have no effect upon the splicing because meantime the thrust bar 460 will have been elevated by an appropriate cam on the pattern drum 120 to hold the splicing yarn guide F out of yarn feeding position. The adjusting, that is, intermittent turning of the disks 53, 54 will continue until the idling point 68 reaches the feed pawl 58, whereupon the latter will ride on that idling point, until the splicing in the next stocking is to begin, whereupon the operations before described will be repeated.

I claim as my invention:—

- 15 1. A circular knitting machine, having needles and yarn guides, including a splicing yarn guide, in combination with a variable cam adapted to control said yarn guide, said cam comprising a central disk and two side disks turning thereon and geared together to turn in opposite directions and an automatic pawl and ratchet feed device to act upon one of the disks.
- 20 2. A circular knitting machine, having needles and yarn guides including a splicing yarn guide, in combination with a variable cam adapted to control said splicing yarn guide, said cam comprising a central disk, two side disks, a pinion carried by the central disk and gearing the two side disks together and an automatic pawl and ratchet feed device to act upon one of the disks.
- 25 3. A circular knitting machine, having needles and yarn guides, including a splicing yarn guide, and pattern mechanism controlling the active and inactive positions of the yarn guides at different stages of the knitting in combination with a variable cam controlling the periods of active and inactive 30 positions of the splicing yarn guide during each revolution of the knitting head, means for automatically adjusting the said cam and devices for idling said adjusting means at certain times under the control of the pattern mechanism.
- 35 40 45

In testimony whereof I have signed my name to this specification.

HARRY SWINGLEHURST.
